UNITED STATES PATENT OFFICE.

GEORGE F. JOHNSON, OF ENDICOTT, NEW YORK.

SHOE.

Application filed February 8, 1924. Serial No. 691,415.

This invention is an improvement in a shoe and the principal object thereof is to provide a strong and durable shoe combining the desired qualities of a leather 5 outing shoe with those of a canvas rubber soled shoe which shoe will be light, durable and comfortable on the foot of the wearer, and will be adequately reenforced at the places where it receives the greatest strain. 10 Another object is to produce a canvas or cloth shoe which in lieu of the usual vamp, is provided with a toe piece having a rearwardly extended free portion, adapted to be over-lapped by the free edges of the 15 sides, the front ends of which sides extend forwardly to the toe of the shoe. A further object is to provide adequate means for maintaining the forward extensions of the sides in close engagement with the toe 20 piece, so as to insure a shapely appearance and a weather-tight joint between the parts.

I will explain the invention with reference to the accompanying drawings which illustrate the same to enable others to adopt 25 and use the same, and will summarize in the claims, the novel features of construction and novel combinations of parts for which protection is desired.

In the accompanying drawing:— 30 Figure 1 is a perspective view illustrating a shoe constructed in accordance with the invention.

Figure 2 is a transverse section on line 2—2, Fig. 1.

Figure 3 is a longitudinal sectional view of the shoe.

Referring to the drawing, 10, 10^a, designate the cloth or heavy canvas upper stock forming the sides or upper of the shoe, 40 which are provided at their forward ends with reduced extensions 12, 12^a which terminate contiguous to the toe portion of the sole S, but are preferably separated by a substantial space. The front edges of said sides are reenforced by leather strips 13, 13^a, which are provided with the usual lacing eyelets, and the bottom edges of the sides are reenforced by leather side braces or strips 14, 14^a, the top edges of which are 45 stitched as indicated to the said sides 10, 10^a, the lower edges thereof being turned in and sewed to the sole S, together with the contiguous edges of the said side pieces, in a manner well understood in the art. It 50 will be noted that the toe ends of the leather strips 13, 13^a are curved down-

wardly, and overlap the contiguous ends of the reenforcing side braces or strips 14, 14^a, the adjacent portions of the sides 10, 10^a, and strips 13, 13^a and side braces 14, 14^a 60 being secured to the adjacent portion of the toe 17 by suitable stitching 16.

The meeting edges of the sides 10, 10^a at the rear of the shoe are joined together and reenforced by an overlapping leather back-stay 18, which is stitched to the adjacent portions of the sides 10, 10^a in the usual manner.

The toe of the shoe is constructed of an independent piece of leather 17, having its 70 front edge suitably shaped to conform to the toe edge of the sole S, and lasted to the said sole in the same manner that the side pieces are lasted thereto. The stitching 16 also serves to attach the contiguous 75 ends of strips 13, 13^a, and 14, 14^a, to the free side edges of the toe piece 17. A substantial portion of the toe piece, indicated at 17^a is extended rearwardly in a position to be overlapped by the free edges of extensions 12, 12^a, said extension 17^a being free, and having attached thereto a tongue 19.

Any desired type of sole may be employed. It is preferred however, to construct the sole of a live rubber outer sole 20, having a heel portion 20^a, a leather middle sole 21, and a leather inner sole 22, secured to the shoe upper and to each other, in any suitable manner, and above the inner sole 22, is preferably a smooth leather sock lining 23. The sides may, if desired, be provided with leather ankle patches 24, and the rear part of the shoe with an inside leather counter pocket 25.

In order to further enhance the durability of the shoe and to further secure the outsole, middle sole, and upper sole together, I provide a row of spaced nails 26, around the edge of the sole of the shoe, 100 said nails passing through the three above mentioned soles, and firmly securing the same together, to lessen the strain on the sole stitching.

If desired, however, any method of fastening the rubber sole 20 to the middle leather sole 21 may be used, and the fastening nails 26 may be dispensed with; for example, the outer rubber sole 20 may be cemented to the middle leather sole 21, or 105 fastened in some other manner than by the nails 26, and if cemented, the middle sole

21 would be secured to the inner sole 22 in any desired manner. The particular manner in which the sole is applied to the shoe does not form any part of the present invention.

In practice, the toe piece 17 is so shaped that when the shoe is applied to the wearer, the extension 17^a will be raised to a position to be overlapped and engaged by the 10 free edges of the sides 10 and 10^a, in such a manner that the usual lacing will draw the opposed free edges of the sides together. Thus they will be maintained in a close overlapping contact with the toe 17 and tongue 15 19 so as not only to provide a weather-proof joint, but also to insure a neat appearance.

The advantages of the invention will be understood by those skilled in the art to which it belongs. By constructing the toe 20 pieces so as to be overlapped by the extensions of the side piece, the usual vamp is dispensed with, a finished appearance is attained, and a weather-tight shoe provided. By doing away with the vamp, and substituting the side extensions and independent toe piece, the cost of manufacture will be much less than that of the vamp-type shoe.

My novel shoe combines the desired qualities of a leather outing shoe with those of a 30 canvas rubber soled shoe; also the qualities of lightness, and long-wearing, and can be repaired like an ordinary leather bottom shoe.

Having thus explained the nature of the 35 invention and the manner of constructing the same, although without attempting to set forth all of the forms in which it may be made, what I claim is:

1. A shoe of the character described comprising a sole, side pieces secured thereto and provided with forward extensions separated at the toe end of the shoe, a toe piece having one edge secured to the sole 40 between said extensions and having a portion extending rearwardly in a position to be overlapped by the free edges of said

side extensions, a tongue secured to the free end of said toe piece, and reenforcing leather strips secured to the lower edges of the side pieces and to the sole, and having their 50 forward ends secured to said toe piece.

2. A shoe of the character described comprising a sole, side pieces secured thereto and provided with forward extensions separated at the toe end of the shoe, a toe 55 piece having one edge secured to the sole between the said extensions and having a portion extending rearwardly in a position to be overlapped by the free edges of the side extensions, a tongue secured to the free end of said toe piece, reenforcing leather strips secured to the lower edges of the side pieces and to the sole, and having their forward ends secured to the sides of said toe piece, and leather eyelet strips secured to 60 the forward edges of the side pieces, and having their toe ends attached to the toe piece and the contiguous ends of said reenforcing strips.

3. A shoe of the character described comprising a sole, side pieces secured to the sole at their lower edges and having forward extensions terminating contiguous to the toe end of the sole, said extensions being separated by a substantial space, reenforcing 75 strips secured to the lower portions of the side pieces and also attached to the sole, lacing strips secured to the front edges of the side pieces, and conforming to the contour of said edges, a toe piece located in the space between said extensions and having one edge secured to the sole, said toe piece having a rearwardly extended free portion located in a position to be overlapped by the said side extensions, the contiguous ends 80 of the reenforcing strips and lacing strips being secured to each other and to contiguous free edges of the toe piece, and a tongue secured to the free end of the toe piece.

In testimony that I claim the foregoing 85 as my own, I affix my signature.

GEORGE F. JOHNSON.
